UNITED STATES PATENT OFFICE.

DAVID H. ZELL, OF BROOKLYN, NEW YORK.

DESIGN FOR A COVERING FOR VANITY CASES OR ANALOGOUS RECEPTACLES.

Application filed November 15, 1928. Serial No. 28,885. Term of patent 3½ years.

To all whom it may concern:

Be it known that I, DAVID H. ZELL, a citizen of the United States, residing at Brooklyn, in the county of Kings and State of New York, have invented a new, original, and ornamental Design for Covering for Vanity Cases or Analogous Receptacles, of which the following is a specification, reference being had to the accompanying drawing, forming part thereof.

The drawing represents a partial plan view showing my new design, it being understood that the remainder is identical. The article consists of a thin flexible sheet of leather or other fibrous material capable of use as a covering and to one side of which surface ornamentation is applied.

I claim:

The ornamental design for a flexible covering for vanity cases or analogous receptacles, as shown and described.

DAVID H. ZELL.
